METHOD OF PREPARATION OF SULPHAMIC AROMATIC ACIDS

Robert Lazare Lantz, Paris, and Gilbert Henri Victor Kremer, Erment, France, assignors to Compagnie Francaise des Matieres Colorantes, Paris, France, a French body corporate

No Drawing. Application September 21, 1954,
Serial No. 457,536

Claims priority, application France October 5, 1953

4 Claims. (Cl. 260—500)

It is known that the reaction of 4-nitroso-phenyl-amino-benzene with sodium sulphite yields an N-phenyl-diamino-benzene sulphonated in the nucleus (Frankel and Spiro G. P. 77536 Friedlaender 4 p. 87). It is to be noted that in the foregoing method of Frankel and Spiro a solution of the nitroso derivative in an excess of caustic soda is used.

It has now been found that if the said nitroso derivative is treated with a salt of sulphurous acid, in the absence of caustic alkali and in a medium capable of dissolving at least partially, one of the two starting materials, there is formed equally a sulphonated derivative of 4-amino-diphenylamine but one in which the sulphonic group is found on the primary amino group; the reaction has brought about the transformation of the nitroso group —NO of the primary material into an amino-sulphonic group —NHSO₃H. It has further been found that this latter reaction is general, and that it allows of obtaining derivatives sulphonated on the primary nitrogen of the 4-amino-diarylamines, starting from the 4-nitroso-diarylamines.

Amongst the para nitrosated diamines to which the present process applies may be mentioned those derived from symmetrical or unsymmetrical aryl amines, in particular 4-nitroso-diphenylamine, 4-nitroso-3:3'-dimethyl-diphenylamine, 4-nitroso-3-methoxy-diphenylamine, and 4-nitroso-4'-methoxy-diphenylamine.

Examples of salts of sulphurous acid which may be used are in particular the water soluble salts of this acid, like the alkali salts and the salts of nitrogen bases.

The medium is considered to be free from caustic alkali if the totality of the salts and other ionisable products which it contains, contains fewer equivalents of alkali metals than equivalents of acids, the initial nitroso derivative not being reckoned as an acid.

If alkali salts of sulphurous acid are alone used, it is advantageous to use a bisulphite eventually mixed with a sulphite destined to change the pH of the medium, for this purpose another alkali salt can also be added to the solution on condition of not introducing caustic alkali. Amongst the salts of nitrogen bases which may be used, can be mentioned those of ammonia, of aliphatic, primary, secondary or tertiary amines such as mono-, di-, and trimethylamine, di-ethylamine, aromatic amines such as aniline, heterocyclic bases such as pyridine, its homologues or technical mixtures containing these products. There can moreover be used the mixture of several salts of sulphurous acid, for example, the mixture of an alkali salt and of a salt of a nitrogen base of this acid.

It has also been found that in many cases the yields are improved by adding to the reaction medium nitrogen compounds. Amongst these may be mentioned the bases mentioned in the foregoing paragraph and amides such as formamide. The salt forming nitrogen bases can therefore occur in the reaction medium, in part in the state of salts of sulphurous acid, and partly in the free state. It must

2

be noted that the presence of these bases in the free state does not supply caustic alkalinity to the medium. The foregoing nitrogen compounds may be used singly or in admixture.

5 Besides the foregoing products there may be added organic solvents such as methyl, ethyl, propyl and butyl alcohols. There can even be used as reaction medium solely alcohol.

The sulphamic acids obtained are valuable materials 10 for the dyestuffs industry, or for the industry of dyeing fabrics and in particular for the preparation of oxidation dyestuffs on the fibre.

The following examples in which the parts indicated, in the absence of indications to the contrary, are parts by 15 weight will illustrate the invention without limiting it.

Example 1

There is added 100 parts of nitroso-4-phenylamino-benzene in a mixture heated to 80° C. and agitated containing 142 parts of ammonium sulphite in solution in 1000 parts of water and 1500 parts by volume of ethyl alcohol. The same conditions are maintained for 2 hours, then 110 parts of anhydrous sodium carbonate are introduced, and the alcohol and part of the water is distilled off. To the 25 solution obtained, brought to a volume of 1000 parts, 100 parts of sodium chloride are added and the precipitate formed separated by filtering at 15–20° C. The product thus obtained consists of the sodium salt of N'-phenyl-1:4-diaminobenzene-N⁴-sulphonic acid.

30 A similar result is obtained by replacing the solution of ammonium sulphite by a similar solution containing an equimolecular quantity of di-ethylamine-sulphite.

Example 2

35 A mixture of 605 parts by volume of a solution containing 429 gr. of sodium bisulphite per litre, 300 parts by volume of a solution containing 200 g. of gaseous ammonia per litre, and 700 parts of pyridine is heated to 80° C. while agitating, and there is added thereto 200 parts of 40 nitroso-4-phenylamino-benzene. After agitating the resulting mixture at the foregoing temperature for an hour and a half 75 parts of carbonate of sodium are introduced, after which the pyridine is distilled off. The mixture is diluted to a volume equal to 1000 parts and is salted with 45 200 parts of sodium chloride. The sodium salt of N¹-phenyl-1:4-diaminobenzene-N⁴-sulphonic acid precipitated, is filtered.

50 By operating in the same manner with 4-nitroso-3:3'-dimethyl-diphenylamine, there is obtained the sodium salt of N¹-(3¹-methyl-phenyl)-1:4-diamino-3-methylbenzene-N⁴-sulphonic acid which after crystallisation in water and alcohol, forms small cleat greyish blue plates. Hydrolysed by boiling dilute hydrochloric acid and acetylated they yield 4-acetylamino-3:3'-dimethyl-diphenylamine of M. P. 55 147° C.

The use as starting material of 4-nitroso-3-methoxy-diphenylamine yields the sodium salt of N¹-phenyl-1:4-diamino-3-methoxybenzene-N⁴-sulphonic acid. The product recrystallised from a mixture of water and alcohol 60 consists of pale bluish flakes. By hydrolysing the product obtained and acetylating the base formed, there is obtained 4-acetylamino-3-methoxy-diphenylamine of M. P. 172° C.

With 4-nitroso-4'-methoxy-diphenylamine there is obtained under the same conditions the sodium salt of N¹-(4'-methoxyphenyl)-1:4-diaminobenzene-N⁴-sulphonic acid. After crystallisation in alcohol it forms pale bluish flakes. After desulphonation there is obtained 4-acetylamino-4'-methoxy-diphenylamine, which melts at 142° C.

Example 3

In a boiling mixture of 100 parts of 50% ethyl alcohol

and 80 parts by volume of a solution containing 520 gr. of sodium bisulphite per litre, there is added 20 parts of 4-nitroso-diphenylamine, and the boiling is allowed to continue for 20 minutes. The alcohol is distilled off, and the remaining mixture is filtered hot, and the volume brought to 200 parts with water; 20 parts of sodium chloride are then added. By filtering at 15-20° C. there is obtained a crystalline precipitate of the sodium salt of N¹-phenyl-1:4-diaminobenzene-N⁴-sulphonic acid.

Example 4

There is heated to 80° C. the mixture formed by 66 parts by volume of a solution containing 370 g. per litre of ammonium sulphite, 14 parts of water and 73 parts of pyridine, then there is added thereto in 10 minutes 20 parts of 4-nitroso-diphenylamine. After having further heated the mixture for 1 hour to the same temperature it is treated as in the foregoing examples. There is thus obtained a precipitate of the sodium salt of N¹-phenyl-1:4-diaminobenzene-N⁴-sulphonic acid.

The same compound may be prepared by operating in a like manner, but replacing the pyridine by the same volume of formamide.

Example 5

There is introduced progressively 10 parts of 4-nitroso-diphenylamine into a mixture heated to boiling and stirred, containing 16.8 parts of ammonium sulphite crystallised with one molecule of water in suspension in 50 parts of absolute alcohol. The boiling is kept up till the disappearance of the yellow colour of the nitroso-derivative then 10.6 parts of anhydrous sodium carbonate is added and 100 parts of water, and the organic solvent distilled off. The solution obtained is diluted to a volume equal to 75 parts, it is salted out with 10 parts of sodium chloride and the precipitate of the sodium salt of N¹-phenyl-1:4-diaminobenzene-N⁴-sulphonic acid filtered at 15-20° C.

By replacing the absolute alcohol by the same quantity of the azeotropic mixture of water and ethyl alcohol there is obtained a like result.

We claim:

1. A process for the preparation of a compound selected from those having the following general formula:

in which X and Y each represent a member selected from the group consisting of the hydrogen atom and the methyl and methoxy radicals, which comprises reacting, by heating between 70° C. and 100° C. a nitroso derivative selected from those having the following general formula:

in which X and Y have the same significance as above, with a salt of sulphurous acid selected from the group consisting of the alkali metal salts and the nitrogen base salts, in the absence of caustic alkali, and in a medium which will dissolve at least partially one of the starting materials.

2. A process for the preparation of a compound selected from those having the following general formula:

in which X and Y each represent a member selected from the group consisting of the hydrogen atom and the methyl and methoxy radicals, which comprises reacting, by heating between 70° C. and 100° C., a nitroso derivative selected from those having the following general formula:

10 in which X and Y have the same significance as above, with a salt of sulphurous acid selected from the group consisting of the alkali metal salts and the nitrogen base salts, in the absence of caustic alkali, and in the presence of water and a free nitrogenous base.

15 3. A process for the preparation of a compound selected from those having the following general formula:

in which X and Y each represent a member selected from the group consisting of the hydrogen atom and the methyl and methoxy radicals, which comprises reacting, by heating between 70° C. and 100° C., a nitroso derivative selected from those having the following general formula:

30 in which X and Y have the same significance as above, with a salt of sulphurous acid selected from the group consisting of the alkali metal salts and the nitrogen base salts, in the absence of caustic alkali, and in the presence of water and a water-miscible organic solvent.

35 4. A process for the preparation of a compound selected from those having the following general formula:

40 in which X and Y each represent a member selected from the group consisting of the hydrogen atom and the methyl and methoxy radicals, which comprises reacting, by heating between 70° C. and 100° C., a nitroso derivative selected from those having the following general formula:

45 in which X and Y have the same significance as above, with a salt of sulphurous acid selected from the group consisting of the alkali metal salts and the nitrogen base salts, in the absence of caustic alkali, and in the presence of an alcohol.
